(57) **CLAIM**

The ornamental design for a lighting fixture, as shown and described.

DESCRIPTION

FIG. 1 is a front left perspective view from below of a lighting fixture according to the new design;

FIG. 2 is a front right perspective view from above thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a front left perspective view from below thereof, but shown illuminated;

FIG. 10 is a front right perspective view from above thereof;

FIG. 11 is a front elevational view thereof;

FIG. 12 is a right side elevational view thereof;

FIG. 13 is a left side elevational view thereof;

FIG. 14 is a rear elevational view thereof;

FIG. 15 is a top view thereof; and,

FIG. 16 is a bottom view thereof.

The broken lines in the drawings illustrate portions of lighting fixture and form no part of the claimed design.

The breakaway lines in the figures, shown as broken lines, indicate a symbolic break in the length of the design indicating no specific height. The appearance of any portions of the article between these break lines forms no part of the claimed design.

The stippling shown in FIGS. 9-13 is solely for the purpose of illustrating the appearance of illumination and does not represent texture or surface ornamentation.
